CATHODE-RAY OSCILLOGRAPH

Ernst Ruska, Berlin-Spandau, and Emil Hentschel, Falkensee, near Berlin, Germany, assignors to Siemens & Halske Aktiengesellschaft, Munich and Berlin-Siemensstadt, Germany, a German corporation

Application January 31, 1951, Serial No. 208,766
In Germany November 26, 1948

6 Claims. (CL 315—16)

1

This invention is concerned with a cathode-ray oscilloscope.

It is customary in cathode-ray oscilloscopes to use for the focusing of the electron beam electronic lenses which are disposed in the beam path between the beam generator and the beam deflection plates. The lenses employed for this purpose may be of the electrostatic or of the electromagnetic type.

In accordance with the invention, there is provided between the beam generator and the deflection plates an electronic lens system comprising two electrostatic lenses, namely, a first electrostatic lens having a short focal range for producing a reduced image of the cathode spot, and a second electrostatic lens forming ahead of the deflection plates an immersion lens which utilizes said reduced cathode spot as a source of electrons for focusing the beam. The first-noted lens comprises two outer electrodes lying on the same potential and a second electrode lying on a different potential. The immersion or focusing lens is formed by the anode and an associated electrode.

The reduced image of the cathode spot is produced by the first-noted lens ahead of the immersion or focusing lens, thus furnishing a particularly small and fine electron source spot for the electron beam, making it possible to focus the tracing point upon the viewing screen as a very fine, sharply defined point.

In accordance with another object of the invention, the central electrode of the individual electrostatic lens is placed at the cathode potential, while its two outer electrodes are placed at a potential lying between the cathode and the anode, preferably approximately at half of the anode voltage.

This latter feature permits the following structural embodiment of the lens system which may be mentioned by way of example: A first acceleration system for the electrons is formed by the Wehnelt-cylinder of the beam generator and an electrode placed at half of the anode voltage. In the path of the beam serially succeeding this first acceleration system is disposed the first lens which reduces the size of the cathode spot. A second acceleration system is formed by the immersion or focusing lens disposed serially with respect to the first lens but ahead of the deflection plates. An electrode of said second acceleration system is disposed ahead of the anode and is placed at half of the anode voltage.

The subdivision of the anode voltage provides for an electrically safe structure which is of im-

2

portance, e. g., in applying the invention in the case of heavy-duty cathode ray oscilloscopes operating with an anode voltage amounting, for example, to 25 kv., so as to obtain high tracing speed.

A further object of the invention is to provide a structurally particularly simple arrangement of the various electrodes of the lens system by the use of two metallic cylinders carrying half of the anode voltage. These cylinders have preferably semi-spherical ends forming apertures for the passage of the beam, serving as electrodes, one of said cylinders forming electrodes coacting respectively with the Wehnelt-cylinder and the central electrode of the first lens, and the other cylinder forming electrodes respectively coacting with the central electrode of the first lens and with an electrode of the second lens.

The above-mentioned metallic cylinders are provided with axially spaced circular mounting disks which are supported in insulated relationship by ceramic members disposed inside the tube. It is advantageous, for the purpose of increasing the creepage or leakage path, to support by means of separate ceramic tubing the mounting disk facing the Wehnelt-cylinder and the mounting disk facing the anode. These separate ceramic tubing members may be supported by insulating members extending from the other mounting disk.

The objects indicated above and additional objects and features will become apparent from a description of an embodiment of the invention which will presently be rendered with reference to the accompanying drawings. In these drawings,

Fig. 1 shows a heavy duty cathode-ray oscilloscope in diagrammatic longitudinal sectional view; and

Fig. 2 represents a diagrammatic transverse section taken approximately along lines A, B of Fig. 1.

The beam generator comprises the glow cathode 1 and the Wehnelt-cylinder 2. Numeral 3 indicates the anode. As shown, the anode is disposed directly facing a first pair of deflection plates 4 to which is connected the voltage to be measured. Numeral 5 designates an intermediate shield carrying marginal angles at both sides. Successively in the path of the beam is disposed the second pair of deflection plates 6 and a terminal shield 7 which is likewise provided with marginal angles.

Two metal cylinders 8 and 11 are built into the tube to form the lens system. The opposite

ends of these cylinders are semi-spherical and are provided with apertures for the passage of the beam. These cylinders form in this manner the semi-spherical electrodes 9-10 and 12-13, respectively. At 14 is indicated the central electrode of the individual lens, referred to before as the "first lens," which has, in accordance with the invention, a short focal range to reduce the size of the cathode spot. The electrodes 10 and 12 form the coaxing outer electrodes of this lens. The anode 3 on its upper side likewise carries a semi-spherical terminal electrode member 15 which faces the electrode 13.

The above described electrodes form a first acceleration system for the electrons comprising the Wehnelt-cylinder 2 and the electrode 9, which is placed on one-half of the anode voltage. In series relationship thereto is the individual cathode spot reduction lens comprising the electrodes 10, 14 and 12. Serially related thereto, within the path of the beam, is disposed the immersion or focusing lens comprising the electrodes 13 and 15 forming a second acceleration system.

The various electrodes are secured by means of circular disks 16-23, inclusive, which are in turn mounted by means of ceramic members 24. Associated with the cylinders 8, to obtain proper centering thereof, is the disk 18. The cylinder 11 is held in a similar manner by the disk 21 and the disk 22.

In order to increase the leakage or creepage path, the disks 18 and 22 are separately supported by ceramic members 26 which are in turn secured to the mounting disks 19 and 21.

The conductor 50, which connects the disks or plates 19 and 21, is carried through a separate opening 51 in the disk 20.

The parts so far described are built into the envelope of the tube 27 which carries a viewing screen 28 at its lower end. The electrical conductors are carried in a vacuum-tight manner through the upper tube wall 29 and through the laterally disposed inlets 30, 31, 32, respectively.

A voltage divider 33 may be provided, as shown, to supply the various potentials. The heating current for the cathode may be supplied from the battery 34 or from a suitable commercial current source. Numerals 35, 36 indicate the cathode terminals; 37 is the conductor for the Wehnelt-cylinder; and 38 carries the current for the central electrode 14 of the individual cathode spot-reducing lens.

The cylinders 8 and 11 are connected to one-half of the anode voltage over the conductor 39. The anode 3 is connected to the voltage divider over the line 40. The intermediate shield 5 and the terminal shutter 7 are at the same potential over the conductors 41-42. The commercial current source is connected at 44, and the first pair of deflection plates 4 is connected with such source over the conductors 45, 46. Numeral 47 indicates a device provided for deflection, depending on a time factor. The two deflection plates are for this purpose connected with the device 47 over the lines 48-49.

The electrodes 2 and 9 accelerate the electrons to one-half of the anode potential. The lens 10, 14, 12 forms the cathode spot in front of the immersion lens 13, 15, on a reduced scale, and the immersion lens focuses the electron beam in usual manner upon the viewing screen 28.

As contrasted with the embodiment shown in the drawings, in which the electrodes 9-10 and 12-13 are associated with common supports 8

and 11, it is of course possible to secure these electrodes each individually upon separate mounting disks which may be secured to the outer holding or mounting members 24.

5 Some of the aspects of the invention may be useful in cathode-ray tubes aside from the specific use thereof in an oscilloscope, and it is understood, therefore, that the disclosure should be given corresponding latitude.

Changes may be made within the scope and spirit of the accompanying claims.

We claim:

1. In a cathode-ray oscilloscope having beam-generating and beam-deflecting means, a pair of serially related electrostatic lenses disposed between said beam-generating and -deflecting means, one of said lenses forming an immersion lens comprising an anode and a coaxing electrode disposed in the beam path ahead of said deflecting means for focusing said beam, said other lens being disposed in the beam path ahead of said immersion lens and having a short focal range to produce a reduced image of the cathode spot which serves as an electron source 25 for said immersion lens.

2. The structure defined in claim 1, wherein said second-noted lens comprises a central electrode and two outer coaxing electrodes, means for placing said central electrode at cathode potential, and means for placing said two outer electrodes at one-half of the anode potential.

3. The structure defined in claim 1, wherein said beam-generating means comprises a Wehnelt-cylinder, a coaxing electrode forming with 35 said Wehnelt-cylinder a first electron acceleration system, means for placing said coaxing electrode on one-half of the anode voltage, said second-noted lens being disposed in serial relationship with said first acceleration system, said immersion lens forming a second electron acceleration system and comprising an electrode which is disposed ahead of the anode and is placed at one-half of the anode voltage.

4. The structure defined in claim 1, wherein 45 said beam-generating means comprises a Wehnelt-cylinder, a pair of metal cylinders, means for placing said cylinders on one-half of the anode voltage, said cylinders having apertured ends formed in semi-spherical shape, the ends 50 of one of said cylinders forming coaxing electrodes for said Wehnelt-cylinder and for an electrode which forms the central electrode of said second-noted lens, respectively, and the ends of 55 said other cylinder forming electrodes for coaction with said central electrode of said second-noted lens and the anode, respectively.

5. The structure defined in claim 1, wherein 60 said beam-generating means comprises a Wehnelt-cylinder, a pair of coaxially serially disposed metal cylinders forming electrodes for coaction with said Wehnelt-cylinder and with an electrode which forms the central electrode of said second-noted lens and for coaction with said central electrode and the anode, respectively, 65 means for securing said metal cylinders each at a plurality of axially spaced points comprising circular mounting disks, and means for separately securing the ends of said disks which face said Wehnelt-cylinder and said anode, respectively.

6. A cathode-ray oscilloscope comprising beam-generating means having a cathode, a plurality of electrodes disposed serially in succession in the path of the beam produced by said beam-generating means, said electrodes comprising 70 in the order named, a first electrode coaxing

with said beam-generating means and forming therewith a first electron acceleration lens, a second, third and fourth electrode forming an individual lens of short focal range for reducing the image of the cathode spot, a fifth electrode coacting with a sixth electrode and forming therewith a focusing lens constituting a second electron acceleration system, the reduced cathode spot produced by said individual lens being utilized by said focusing lens as an electron source, an anode coacting with said sixth electrode, and beam-deflection means serially related to said anode.
